UNITED STATES PATENT OFFICE.

AMOS FREDERICK DIXON, OF NEWARK, NEW JERSEY, ASSIGNOR, BY MESNE ASSIGNMENTS, TO WESTERN ELECTRIC COMPANY, INCORPORATED, A CORPORATION OF NEW YORK.

COUNTING APPARATUS.

1,254,661.

Specification of Letters Patent. Patented Jan. 29, 1918.

Application filed May 24, 1915. Serial No. 30,004.

To all whom it may concern:

Be it known that I, AMOS FREDERICK DIXON, a citizen of the United States, residing at Newark, in the county of Essex 5 and State of New Jersey, have invented certain new and useful Improvements in Counting Apparatus, of which the following is a full, clear, concise, and exact description.

10 This invention relates to counting apparatus, and its principal object is to provide an improved word and character counter particularly adapted for keyboard machines such as typewriters, perforators and the 15 like.

In accordance with the general features of this invention, provision is made whereby keys adapted to control the production of two different characters, as for example, a 20 letter and a digit, will not, in the first instance, cause a registration, while in the second case a registration will be made. Registrations of actual words are produced through the agency of a key which controls 25 the formation of the proper space between adjacent words. An arrangement of this character is especially desirable in telegraphic work where, in order to make the required charges and provide proper records, a count must be made of the number 30 of words in each message. In making such counts, it is customary to register actual words and also arbitrary words, such as digits, punctuation marks, etc. Provision is 35 also made for the resetting of the register mechanism at the will of the operator in an accurate and exceedingly simple manner.

More specifically, the invention comprises an improved electromagnetically actuated 40 registering mechanism controllable by keys through suitable mechanical or circuit connections. The preferred arrangement is such that the manipulation of a so-called double-case key, to control the production 45 of a letter, will not cause a registration, the registration of actual words being controlled at their conclusion, by the space key. On the other hand, however, when a double-case key is to be manipulated to control the 50 production of another character, as, for example, a single numeral or punctuation mark, a preparatory key, which has first been manipulated, prepares for the operation of electromechanical registering mechanism, whose operation is subsequently ef-

fected by the manipulation of the desired character key. The registering mechanism may comprise a plurality of number wheels successively moved to advance the count, each wheel being provided with a restoring 60 device which is allowed to become operative upon the manipulation of a lever, which relieves the wheels from the influence of a holding pawl and the advancing pinions.

The above and other objects of this invention will be fully set forth in the following description and claims, and will be more readily understood by reference to the accompanying drawings, in which Figure 1 is a diagrammatic representation of the circuit connections, a part of the keyboard mechanism of a perforator being shown in perspective. Fig. 2 is a plan, in partial section, of the mechanism of the counting apparatus, and Fig. 3 is a section thereof on 70 the line 3—3 of Fig. 2.

The keyboard mechanism may be of any desired and suitable form and arrangement, the keys controlling either directly or indirectly the production of a written message. 80 Thus a key lever 5 is adapted to control the production of letter "A," and since, as shown, it is adapted to control this character only, it is what is commonly called a "single case" key. A key lever 6 is adapted 85 to control the production of both letter "W" and numeral "2," and is, therefore, a "double case" key.

In the particular form of keyboard machine disclosed, the depression of a double 90 case key normally causes the production of the corresponding letter and in order that it may control the production of the corresponding digit, punctuation 95 mark, etc., it is first necessary to depress a "figure" or shift key 7. After once depressing this shift key, each subsequent depression of a double case key will cause the production of the corresponding digit, punctuation mark, etc., until the "letter" 100 or unshift key 8 is depressed. The spacing between adjacent words is effected by the depression of a suitable space key 9.

The keyboard disclosed is a type commonly employed in the printing telegraph 105 art and is known as a "free keyboard," because all keys return to normal immediately after being depressed and none of the keys are latched or locked in their depressed position. The shift key in addition to 110

closing an energizing circuit through a circuit controlling relay 31, shifts the paper platen or printing mechanism which is then mechanically locked in its shifted position 5 until the unshift key 8 is actuated.

All of the keys, except the space key, may be pivoted on a rod 10, and the space key may be pivoted on a suitable rod 11. Since the mechanism or system, whereby any key 10 may control the production of a letter or character, forms no part of this invention, no explanation is made of any particular arrangement.

Beneath and lying transversely of the key levers, there is located a switch operating bar 15. This bar is formed with a pair of downwardly inclined lugs 16, which are held and may be slidably moved between pairs of suitable pins or friction-reducing rollers 17. 20 One end of bar 15 is associated with a switch 18, one contact of which is connected to a grounded source of energy 19. Downward pressure upon bar 15 causes it to move downward in a direction diagonal to its normal position, and results in the closing of switch 18 for a purpose to be hereinafter explained. Bar 15 may be returned by a spring member (not shown) which moves it upward and to the left when the pressure of a key lever 25 is removed.

Shift key 7 coöperates with a switch 25 in such a manner that when it is depressed the switch is closed. Unshift key 8 is adapted, when depressed, to open a switch 26, and space key 9 is adapted to close a switch 27. Bar 15 is provided with notches beneath all of the single case, the shift and the unshift keys, so that when any of these keys is depressed switch 18 remains unaffected. When, 40 however, a double case key, beneath which there is no notch, is depressed, bar 15 is caused to close switch 18.

One contact of switch 25 is connected to grounded source of energy 30, and the other contact is connected to one terminal of the winding of a relay 31, the other terminal of which is grounded. This relay is provided with a pair of armatures 32 and 33. Armature 32 is joined to the conductor connecting 45 one contact of switch 25 and the winding of relay 31, and coöperates with a front contact connected to one contact of switch 26. The other contact of switch 26 is connected to a grounded source of energy 34. Armature 33 is joined to one terminal of an electromagnet 35 of a registering mechanism 36, the other terminal of which is grounded, and coöperates with back and front contacts. The back contact is connected to one contact 50 of switch 27, the other contact of which is connected to a grounded source of energy 37. The front contact is joined to a contact of switch 18.

The counting apparatus or registering 65 mechanism 36 comprises a suitable frame 40,

which serves as a support for all of the elements and furnishes sockets for the necessary shafts. The count is made on a plurality of number or digit wheels 41, 42 and 43, on which numerals from 0 to 9 appear, as 70 shown. These wheels 41-43 are loosely mounted on a nonrotatable shaft 44, and are properly spaced from the frame 40 by collars 45. Each number wheel 41-43 is provided with a spring drum 50, rigidly secured 75 to one side thereof, and a positioning collar 51. The groove thus formed by a number wheel and its corresponding collar 51 coöperates with the sides of a stop member 52 to keep the wheels in their proper place on the 80 shaft 44. Within each of these grooves there is provided a stop pin 53 which also coöperates with the stop member 52 to limit the restorative movement of the associated wheel, as will be hereinafter described. 85

Within each drum 50 there is a restoring device in the form of a helical spring 54 secured at its inner end to a suitable slot in shaft 44. The outer ends of these springs bear against but are not securely fastened 90 to the inner surfaces of the drums 50. The frictional engagement between springs 54 and drums 50 is, however, sufficient to rotate the wheels in the direction of the arrow of Fig. 3, when allowed to do so as hereinafter 95 explained, but there is no danger of the springs being broken or the apparatus becoming jammed, no matter how many times the wheels are rotated.

Rotary motion is imparted to number 100 wheels 41-43 by electromagnet 35 through the agency of an actuator 55. Electromagnet 35 acts upon an armature 56 pivoted on a shaft 57 to rotate the armature against the tension of a spring 58. This spring 58 105 is secured at one end to a rod 59 supported by frame 40, and at the other end is fastened to armature 56 by an adjustable lug 60. Actuator 55 is pivotally carried by armature 56 through a pivot pin 61, and is normally 110 held in the position shown in Fig. 3 by spring 58. The reciprocatory motion of actuator 55 produces rotary motion in the number wheels through a ratchet wheel 65 which is secured to the units number wheel 115 41. As actuator 55 is moved to the right by armature 56, it engages a tooth of ratchet wheel 65 and rotates it, together with units wheel 41, in a direction opposite to that of the arrow in Fig. 3, until an upwardly projecting lug 66 thereon engages a stop 67 which is secured to the frame 40. When this position is reached the units wheel has been moved a sufficient amount to exhibit the next higher digit thereon. The units wheel is retained in this condition, against the tendency of spring 54 to return it when armature 56 is retracted, by a holding pawl 70. This pawl is pivoted upon a shaft 71 and is normally held in engagement with the teeth of 120 125 130

ratchet wheel 65 by a spring 72. One end of spring 72 is secured to pawl 70 and the other end to a bracket 73, which is carried by the frame 40, and to which stop members 52 are also fastened.

5 In order that the count may be kept by the mechanism shown in units, tens and hundreds, means are provided whereby at the proper time motion is communicated 10 from each number wheel to the next succeeding or higher digits wheel. This means comprises a gear wheel 74 secured to each number wheel, except the last, and provided with only two teeth which are adjacent to 15 each other. Each number wheel, except the first, also carries a gear wheel 75 which is provided with as many teeth as there are numerals upon its corresponding number wheel, in the mechanism shown there being 20 ten such teeth. Coöoperating with each adjacent pair of gear wheels 74 and 75 is a small pinion 76 whose teeth are adapted to engage the teeth of both gear wheels. Since, however, there are but two teeth on wheel 25 74, it is only once during a revolution of units wheel 41 that motion will be communicated to tens wheel 42, and similarly only once during a complete revolution of tens wheel 42 that a step will be communicated 30 to hundreds wheel 43. It is, therefore, apparent that for every ten steps of units wheel 41 the tens wheel 42 will make one step, and for every ten steps of tens wheel 42 the hundreds wheel 43 will make one 35 step. If necessary the number of wheels may be increased as desired. The two pinions 76 are loosely mounted upon the shaft 77 which is carried by and between two bracket arms 78 and 79. These bracket 40 arms are pivotally secured to the frame 40 by suitable pivot screws 80. A downwardly extending portion 81 of the pawl 70 partly embraces the shaft 77 carrying the pinions 76, so that when the shaft 77 is moved by 45 the resetting means, as will be hereinafter explained, the holding pawl 70 is disengaged from its ratchet wheel 65.

In order that the tens and hundreds digits wheels will not be prematurely 50 turned to their normal position, by their restoring devices, after each forward step, means are provided for preventing the backward rotation of any of the pinions 76. These means comprise a lever 85 individual 55 to each pinion 76 and pivotally carried by and between the bracket arms 78 and 79 on a shaft 86. The forward ends of levers 85 are held yieldingly in engagement with the teeth of their coöperating pinions 76 by 60 means of springs 87. One end of each of these springs is secured to frame 40, the other end being fastened to lever 85. The coöperation between levers 85 and their corresponding pinions 76 is such that when a 65 pinion is rotated in the direction of the

arrow shown in Fig. 3, to communicate advancing motion from one number wheel to the next succeeding wheel, this rotation is in no way interfered with by the ends of levers 85. However, after a lever 85 has ridden 70 over the next tooth of a pinion 76, it drops behind this tooth and prevents any backward movement of the pinion; and since each pinion interlocks the teeth of gear wheels 74 and 75, the springs within drums 75 50 are prevented from rotating the number wheels.

In order that the apparatus may be reset after counting the words of a message, means are provided under the control of the 80 operator for simultaneously releasing the number wheels to allow their individual springs to restore them to normal condition, as shown in Fig. 3. This means comprises a manually controlled reset lever 90 which 85 is carried by the free ends of arms 78 and 79. Normally, the free ends of arms 78 and 79 are held elevated by a pair of springs 91, the ends of which are secured to bracket 73, and to a rod 92 extending between arms 78 90 and 79, in such a position that holding pawl 70 and pinions 76 are in engagement with their respective ratchet and gear wheels, as shown in Fig. 3. Whenever the operator, therefore, wishes to reset the wheels to normal, lever 90 is depressed causing the depression of the free ends of arms 78 and 79 and the shaft 77 carried thereby, resulting in the withdrawal of holding pawl 70 and pinions 76 from engagement with their respective wheels. Thereupon the springs within the drums 50 rotate the number wheels in the direction of the arrow shown in Fig. 3 until the stop pin 53 associated with each is engaged by the proper stop 100 member 52, in which condition all of the wheels are at normal.

The operation of the apparatus is as follows: Upon each depression of space key 9 after the completion of an actual word, 110 switch 27 is closed, whereupon current flows from grounded source 37 through switch 27, back contact and armature 33 of relay 31 and electromagnet 35 to ground. Electromagnet 35 thereupon attracts its armature 56 115 causing actuator 55 to engage ratchet wheel 65 to move units wheel 41 forward one step. During the forming of actual words, the depression of the double case keys, to effect the production of a letter, does not result 120 in the energization of electromagnet 35, for, although the depression of each such key causes the closing of switch 18 through the action of bar 15, the closure of this switch cannot complete a circuit for grounded 125 source 19 because of the non-engagement of the front contact and armature 33 of relay 31. Whenever figures, punctuation marks, etc., each one of which is arbitrarily chosen to count as one word, are to be produced, 130

shift key 7 must first be depressed. The depression of this key causes the closing of switch 25, whereupon a circuit is completed from grounded source 30 through the winding of relay 31 to ground. Relay 31 thereupon attracts both its armatures 32 and 33. Armature 32 completes a holding circuit for relay 31 from grounded source 34 through switch 26, front contact and armature 32, 10 through the winding of relay 31 to ground. The attraction of armature 33 prepares a circuit from switch 18 through electromagnet 35, the operative condition of which is insured by the subsequent depression of a double case key which, by closing switch 18, connects grounded source of energy 19 to electromagnet 35, effecting the operation of the registering mechanism. Since relay 31 in attracting armature 32 has provided a holding 20 circuit for itself, after shift key 7 is once depressed registrations will thereafter be made for each depression of a double case key until unshift key 8 is operated. The depression of unshift key 8 opens switch 26 25 breaking the previously traced holding circuit for relay 31, whereupon the armatures 32 and 33 are retracted and the energization of electromagnet 35 is returned to the control of space key 9. During the entire production of figures, punctuation marks, etc., however, the operation of space key 9 cannot cause a registration, since the circuit of switch 27 is open at armature 33. Thus, a double count is impossible. 30 Upon each energization of electromagnet 35, units wheel 41 is advanced one step, as previously described, through the agency of armature 56 and actuator 55, the wheel being retained in each advanced position by holding pawl 70. Upon the tenth step of units wheel 41, gear wheel 74 has made a complete revolution, its teeth engage the coöperating pinion 76, causing this pinion to be rotated one step in the direction of the arrow shown 45 in Fig. 3, and, because of the coöperation of this pinion and gear wheel 75, tens wheel 42 is moved one step. This action continues, tens wheel 42 taking one step for each ten steps of units wheel 41 until the tens wheel 50 makes ten steps, whereupon the hundreds wheel 43 is caused to be moved one step. After the completion of the message, the

operator depresses lever 90, whereupon holding pawl 70 and pinions 76 are removed from engagement with their corresponding ratchet wheel, and the number wheels are returned to their normal position as shown in Fig. 3, as previously described. 55

The invention claimed is:

1. A counting apparatus comprising a registering mechanism, an electromagnet for controlling the operation of said mechanism, a switch, a relay energized by the operation of said switch to partly prepare an operating circuit for said electromagnet, a second switch for completing the operating circuit thus prepared to effect a registration, and an independently actuated switch for effecting the energization of said electromagnet to cause a registration when said relay is deenergized. 70

2. In a counting apparatus, the combination of a registering mechanism, an electromagnet for effecting the operation of said mechanism, an energizing circuit for said electromagnet, a shift key for preparing said energizing circuit, a plurality of double case keys, and means operated by one of said keys for closing a switch in said prepared circuit to effect a registration. 75

3. In a counting apparatus, the combination of a registering mechanism, an electromagnet for effecting the operation of said mechanism, an energizing circuit for said electromagnet, a shift key, means operated by the actuation of said shift key for preparing said energizing circuit, a plurality of double case keys, and means operated thereby for closing a switch in said prepared circuit to effect a registration. 80

4. In a counting apparatus, the combination of a plurality of keys, a registering mechanism, an electromagnet for controlling the operation of said mechanism, an energizing circuit for said electromagnet, a shift key, a relay operated by the actuation of said key for preparing said energizing circuit, and means operated by the actuation of another of said keys for closing said prepared circuit to effect a registration. 95

In witness whereof, I hereunto subscribe my name this 21 day of May, A. D., 1915.

AMOS FREDERICK DIXON.
